His Attorneys.

UNITED STATES PATENT OFFICE

2,466,954

SUSPENSION FOR TACKLING DUMMIES

Grant King, Hamilton, Ohio

Application September 5, 1947, Serial No. 772,395

7 Claims. (Cl. 273—55)

1

This invention relates to a suspension for a tackle bag and more particularly to a shock release mechanism for use in suspending the bag from a movable support.

It is common practice in training football players to use a tackle bag or dummy suspended from a support but when using a conventionally suspended bag for tackling, the players are not called upon to tackle under actual conditions and furthermore it is difficult to determine how effective the tackling of a given player is in comparison with that of another player. This difficulty in gauging a player's tackling ability when using a conventionally suspended tackle bag handicaps the coach in training his men to tackle effectively with the required force. It is an object of this invention to provide an arrangement for suspending a tackle bag in such a manner that the players are required to make tackles more nearly under normal playing conditions and in such a manner that the bag is released from its support in response to a predetermined impact or shock.

A further object of this invention is to provide a shock release mechanism which includes means for adjusting the amount of shock required to effect a release.

Another object of this invention is to provide a durable and inexpensive release mechanism.

Still another object of this invention is to provide an improved arrangement for fastening the tackle bag to the bag supporting structure in such a manner that it is possible to remove or replace parts of the dummy mechanism with the minimum amount of effort and expense.

Another object of this invention is to provide an improved arrangement for swingably supporting the tackling dummy so as to cause the dummy to swing from side to side while moving in a given direction so as to simulate the movement of a football player running down on the football field.

Further objects and advantages of the present invention reside in the construction and combination of parts and in the mode of operation as will be apparent from the following description, reference being had to the accompanying drawings wherein a preferred form of the present invention is clearly shown.

In the drawings:

Figure 1 is an elevational view, partly in section, showing the construction of the bag and the shock release mechanism;

Figure 2 is an elevational view showing the tackle bag separated from the suspending mechanism;

2

Figure 3 schematically shows the tackle bag and the supporting structure for movably supporting the bag;

Figure 4 is an end view of the clutch elements which form a part of the release mechanism; and

Figure 5 is a side view of the same clutch elements shown in Figure 4.

Referring now to the drawings wherein I have shown a preferred embodiment of my invention, reference numeral 18 designates generally a tackle bag or dummy which is adapted to be movably supported from a track 12 (see Figure 3) suspended between suitable supports 14. A carriage mechanism 16 is supported to move along the track 12 and is adapted to serve as a means for suspending the tackle bag 18 in a manner to be described more fully hereinafter. The carriage 16 may be of the type which includes a motor for propelling the carriage from one end of the track to the other much like a traveling crane or it may be of the type which may be manually moved from one end of the track to the other.

The release mechanism used in suspending the bag 18 from the carriage 16 comprises a main supporting element 20 which is swingably supported from the carriage 16 by means of the swivel element 23 which is a standard swivel unit and needs no further description. The element 20 is flared outwardly towards its lower end so as to provide a tapered cam surface 22 which cooperates with the ball or detent elements 24 which form a part of the clutch or cam elements 26. For purposes of illustration, I have shown three similarly constructed clutch elements (see Figures 4 and 5) which are arranged to surround the member 20 in a manner and for a purpose to be described more fully hereinafter. While I have shown three clutch elements, it is obvious that the number of clutch elements used may be varied although I have found that there is an advantage in using three clutch segments arranged as shown in Figures 4 and 5. Each clutch element is provided with a ball socket 28 within which a ball or detent 24 is mounted. The extreme outer end of each socket has a diameter slightly less than the diameter of the ball so as to prevent the ball from falling out. The inner surface of each ball is adapted to slide along the cam surface 22 provided on the member 20 and the outer portion of each ball is adapted to releasably engage within the circumferential groove 30 formed in the socket member 28 which forms a part of the tackle bag assembly and serves as a keeper for the detent balls 24 so as to hold

the bag properly suspended on the support 20 in a given position of the clutch elements, as will be explained more fully hereinafter.

As best shown in Figure 1 of the drawing, a coil spring 34 surrounds the clutch elements 26 and has its ends arranged in engagement with the washer elements 36 and 38 which butt against the shoulders 40 and 42 respectively of the clutch elements. The spring 34 not only assists in holding the clutch elements in assembled relationship but also plays a part in the release of the bag in a manner to be explained more fully herein-after. A spring 44 biases the clutch elements 26 downwardly on the member 20. A pair of washer elements 46 are provided between the lower end of the spring 44 and the upper ends of the clutch elements 26 as best shown in Figure 1. In order to provide means for adjusting the force with which the spring 44 biases the clutch elements 26 downwardly, I have provided a nut 50 which is threaded to the member 20 so as to provide for the necessary adjustments of the spring 44. By adjusting the nut 50, it is possible to vary the amount of shock required for releasing the bag and its associated parts from the supporting member 20.

By virtue of the above described construction and arrangement of elements, it is apparent that a gradual downward pull on the bag merely serves to increase the force with which the balls 24 engage within the channel 30 and consequently effectively prevents removal of the bag from its support in response to an ordinary pull. However, the parts are so arranged that a sudden impact or shock imparted to the bag serves to disarrange the clutch elements 36 and the balls 24 in such a manner that the bag 10 together with the socket 32 may be detached from the supporting mechanism. It will be noted that the three balls are normally uniformly spaced circumferentially relative to the axis of the member 20 as well as the axis of the bag 10 and that when the bag is given a hard blow or shock the clutch elements 26 are free to shift both circumferentially and longitudinally relative to the cam surface 22 so that if the shock is great enough or quick enough, the bag becomes released before the springs 34 and 44 have time to force the parts back into the bag retaining position.

The spring 44 biases the clutch elements 26 downwardly in such a manner that the balls 24 are forced outwardly into engagement with the channel 30 provided in the socket 32 so as to prevent release of the bag assembly from the supporting mechanism when a straight and relatively slow pull is exerted on the bag. However, a sudden impact or jolt on the bag causes the axis of the bag to move out of alignment with the axis of the member 20 and this too facilitates release of the bag. In making an effective tackle, the tackler normally strikes the bag with a hard blow and causes the bag to be lifted slightly with the result that the relative position of the socket 32, the clutch elements 26 and the balls 24 becomes such that the bag is readily released so that the player tackling the bag can carry the bag away with him. The tighter the spring 44 is, the greater becomes the force required for releasing the bag from its support. Consequently, it is possible to adjust the amount of shock or impact required to release the bag.

It will be noted that as the bag assembly including the socket member 32 is pushed upwardly, the clutch elements 26 are pushed upwardly, whereby the balls 24 move toward the

smaller portion of the cam 20. In this relative position of the parts, the balls clear the groove or channel 30 in the socket 32 so that a quick pull on the bag serves to disconnect the bag from its support. After the bag has been removed from its support, it may be replaced very quickly merely by raising the bag upwardly until the socket element 32 slips onto the lower end of the support. In effect, the balls 24 serve as detents for releasably holding the bag in place on the support. As pointed out hereinabove, the nut 50 serves to vary the force with which the balls or detents 24 engage within the channel 30.

In order to avoid injury to the players, I have provided pneumatic means 58 resembling a small automobile or wheelbarrow tire which is arranged as shown so as to surround the element 32. The outer covering 60 for the bag may be made of canvas or any other suitable material and is adapted to be removably supported from the supporting ring 62 carried by the socket element 32 by means of a zipper mechanism 64. The bag 60 may be filled with sawdust or any other materials commonly used in the manufacture of tackling bags.

By virtue of the above described arrangement, it is apparent that the effectiveness of the player's tackling ability may be improved and that the effectiveness of the tackles may be gauged very closely since ineffective tackles result in the bag remaining on the support.

After the bag has been removed, it is easy to replace it merely by lifting upwardly on the bag so as to cause the upper surface of the socket element 32 to shove against the cam elements 26 as to cause the cam elements to move upwardly relative to the element 20 until the distance between the inner surface of the socket opening and the adjacent portion of the cam surface 22 is less than the diameter of the balls 24 at which time the balls 24 will snap into the groove 30 and will hold the bag in place until the bag is again given a shock or blow so as to cause release of the bag.

While the form of embodiment of the invention as herein disclosed, constitutes a preferred form, it is to be understood that other forms might be adopted, all coming within the scope of the claims which follow.

Having thus described my invention, I claim:

1. A tackle bag mechanism comprising in combination, a support, a tackle bag assembly, means for attaching said bag assembly to said support, said bag assembly comprising a hub having a bag supporting ring filler material including a pneumatic tire carried by said hub and having an outer circumference substantially equal to the outer circumference of the main body portion of said bag assembly, a fabric bag enclosing said tire and filler material, and means for attaching said fabric bag to said bag supporting ring.
2. In combination, a support, a tackle bag, means for suspending said tackle bag from said support, said last named means comprising an elongated cam member having an outwardly flared end portion forming a cam surface, and circumferentially spaced radially movable clutch elements slidably supported on said elongated cam member, said clutch elements including portions movable radially outwardly in response to longitudinal movement of said clutch elements on said elongated cam member, said tackle bag including means engageable by said clutch elements in a predetermined relative position of 75 said clutch elements and said elongated member.

3. In combination, a support, a tackle bag, means for suspending said tackle bag from said support, said last named means comprising an elongated cam member having an outwardly flared end portion forming a cam surface, and circumferentially spaced radially movable clutch elements slidably supported on said elongated cam member, said clutch elements including portions movable radially outwardly in response to longitudinal movement of said clutch elements on said elongated cam member, said tackle bag including means engageable by said clutch elements in a predetermined relative position of said clutch elements and said elongated member, and spring means biasing said clutch elements into gripping engagement with said last named means.

4. In combination, a support, a tackle bag, means for suspending said tackle bag from said support, said last named means comprising an elongated cam member having an outwardly flared end portion forming a cam surface, and circumferentially spaced radially movable clutch elements slidably supported on said elongated cam member, said clutch elements including portions movable radially outwardly in response to longitudinal movement of said clutch elements on said elongated cam member, said tackle bag including means engaging said clutch elements in a predetermined relative position of said clutch elements and said elongated member, and spring means biasing said clutch elements into gripping engagement with said last named means, said spring means comprising a coil spring surrounding a portion of said elongated cam member and having one end arranged in engagement with said clutch elements.

5. In combination, a support, a tackle bag, means for suspending said tackle bag from said support, said last named means comprising an elongated cam member connected to said support and having an outwardly flared end portion forming a cam surface, and circumferentially spaced radially movable clutch elements slidably supported on said elongated member, said clutch elements including portions movable radially outwardly in response to longitudinal movement of said clutch elements on said elongated cam member, said tackle bag including a socket element engaged by said clutch elements in a predeter-

mined relative position of said clutch elements and said elongated member, and spring means biasing said clutch elements toward the outwardly flared end of said cam member and into gripping engagement with said socket element, said spring means comprising a coil spring surrounding a portion of said elongated cam member and having one end arranged in engagement with said clutch elements, and means carried by said elongated cam member for adjusting the force of said spring means.

5 6. A tackle bag mechanism comprising in combination, a support, a tackle bag, a tire casing having an outer circumference substantially equal to the outer circumference of the main body portion of said bag, means for attaching said tire casing to said support, and means for attaching said bag to said tire casing, said bag comprising an inturned flange portion at the 10 upper end of said bag for engaging over said tire casing.

15 7. In combination, a support comprising an elongated cam member having an outwardly flared lower end portion forming a cam surface, 20 circumferentially spaced radially movable clutch elements slidably supported on said elongated cam member, said clutch elements including portions movable radially outwardly in response to downward movement of said clutch elements on 25 said elongated cam member, and a tackle bag assembly comprising a bag, a tire casing having an outer circumference substantially equal to the outer circumference of said bag, and means secured to said tire casing for frictionally engaging 30 said clutch elements so as to hold said tackle bag assembly in place on said support in a given 35 position of said clutch elements.
